CLAIM

The ornamental design for a wearable chain, as shown and described.

DESCRIPTION

FIG. 1 is a top plan view of a wearable chain and including an enlarged partial top view showing twelve links; FIG. 2 is an enlarged detail view of a portion of the wearable chain shown in FIG. 1;

FIG. 3 is a detailed perspective view of the wearable chain in FIG. 1 shown in an alternate configuration;

FIG. 4 is a top plan view thereof;

FIG. 5 is a bottom plan view thereof;

FIG. 6 is a front elevational view thereof;

FIG. 7 is a rear elevational view thereof;

FIG. 8 is a right side elevational view thereof; and,

FIG. 9 is a left side elevational view thereof.

The broken lines shown in the drawing views represent portions of the wearable chain which form no part of the claimed design.

1 Claim, 6 Drawing Sheets
